UNITED STATES PATENT OFFICE

124,760

DESIGN FOR A DRESS ENSEMBLE

Edna Freeman, New York, N. Y.

Application November 29, 1940, Serial No. 96,958

Term of patent 3½ years

To all whom it may concern:

Be it known that I, Edna Freeman, a citizen of the United States, residing at Hotel Vanderbilt, Park Ave. and 34th St., New York city, in the county of New York and State of New York, have invented a new, original, and ornamental Design for a Dress Ensemble, of which the following is a specification, reference being had to the accompanying drawing, forming part thereof.

I claim:

The ornamental design for a dress ensemble, substantially as shown.

EDNA FREEMAN.
